UNITED STATES PATENT OFFICE.

GEORGE ACKERMAN, OF SALT LAKE CITY, UTAH, ASSIGNOR OF ONE-THIRD TO
FREDERICK CHARLES BUSH, OF SALT LAKE CITY, UTAH.

SHEET DELIVERY AND STACKER.

1,078,569.

Specification of Letters Patent. Patented Nov. 11, 1913.

Application filed September 10, 1912. Serial No. 719,653.

To all whom it may concern:

Be it known that I, GEORGE ACKERMAN, a citizen of the United States, residing at No. 1416 Blair street, Salt Lake City, in the county of Salt Lake and State of Utah, have invented a new and useful Sheet Delivery and Stacker Specially Adapted for Use on All Standard or Regular Drum Back-Delivery Printing-Presses, of which the following is a specification.

My invention relates to improvements in the mechanism used for the purpose of delivery and stacking of the printed sheets on all standard or regular drum back delivery printing presses, in which my device takes the place of all the complicated machinery comprising the fly system of sheet delivery and the jogger system of sheet stacking; and the objects of my improvement are, first, to secure a better delivery of the sheets by a contrivance containing no small or delicately constructed parts, which are liable to need repairing or replacement; second, to stack the sheets automatically as they are delivered; third, to eliminate all risk of streaking the surface of the printed sheet, especially on illustrated matter; fourth, economy in floor space by assembling the table inside the frame of the printing press instead of it being on the floor; fifth, to secure an easier means of access to the form, while in the press, for the purpose of making corrections in the type or cleaning the same. I attain these objects by the mechanism illustrated in the following drawings.

Figure 1 is an elevation of my improvement. Fig. 2 is an elevation of the sliding gage and sliding gage iron, together with the necessary accessories. (Two of these sliding gages are used on each of my improvements). Fig. 3 is an edge and plan view of the reel cam, together with the shoulder by which it is connected to the frame of the press; the particular shape which I have given to the said reel cam is responsible for the release of the printed sheets by the reel grippers at the best moment for the purposes of my invention. Fig. 4 is a front perspective view of my invention in position to deliver and stack the printed sheets. Fig. 5 is a front perspective view of my invention, showing the front table raised in and held by the table regulators, for the purpose of giving easier access to the form in the press.

Similar letters refer to similar parts throughout the several views.

The table, of wood, A; the table supports (iron) F; the table regulators (iron) G; the finger board (hard wood) B; the table braces (wood) I and the butt hinges J, constitute the framework of my invention. The table A is constructed in two parts, hinged together with four or more two inch butt hinges J, and is beveled on the back so that the finger board B forms an angle of about 76 degrees with the top of the rear portion of the table A. The top edge of the finger board B is scalloped to allow the free action of the reel wheels of the printing press, a a Fig. 4, and the finger board B is also grooved on its front face to accommodate the finger irons D flush with the wood. The finger irons D and the fingers E are formed of one length of metal, but for convenience I prefer to call the portion of said strip of metal which is sunk in the finger board B, as hereinbefore described, as finger iron D, and the portion which is bent forward and over the table A, and is designed to intercept and deliver the printed sheet upon the table A, is designated as finger E, Figs. 1 and 4. The finger irons D are screwed into position as before described on the finger board B, between the reel wheel scallops, and the fingers E are bent and shaped so as to intercept the printed sheet between the rims of the reel wheels and the reel gripper shaft, so that the edge of the printed sheet is under the fingers E about one and one-half inches when released by the reel grippers, Fig. 1. The reel cam, shown in Fig. 3 is so constructed that the reel grippers do not release their hold upon the sheet until the front edge of the sheet is drawn under the fingers E about one and one-half inches. The shoulder, y, is connected to the frame of the press at the same place and in the same manner as the reel cam heretofore in use.

The sliding side gage irons, K, are cast in one piece, the winged portion is fastened to the sliding side gage, C, by screws, (see Figs. 1 and 2) and the lower part has a threaded hole, in which the thumb screw, N, after being fitted with the nut, M, and the washer, L, is screwed from underneath the table, A, at the point s, s, which is a rabbit cut to accommodate the said side gage iron, K. Two of these sliding gages are used on each table, and together with

the loose gage, O, Fig. 1 and the finger board, B, form the essential parts of my stacking device. The loose gage, O, is constructed of a thin sheet of metal, but is not 5 indispensable for the correct stacking of the printed sheets.

I attach my improvement to the printing press in the following manner:—The bolts heretofore used to secure the reel shaft boxes 10 to the frame of the printing press are removed and replaced by longer ones of the same make, which are passed through the holes, Q, at the top ends of the table supports, F, and are secured by nuts on the 15 bolts securing the said reel shaft boxes. The table support, F, is made all in one piece and extends under the rear end of the table, A, (to which it is secured with screws) and is then bent upward at right angles so as 20 to form two arms (or hanging supports for the table) as shown in Figs. 1 and 4 at F. The table regulators, G, are secured by bolts which pass through the frame of the press and the holes shown in the top end of the 25 regulators, G, Fig. 1, and is better illustrated in Fig. 5. The front end of the table A, is strengthened by braces I, I, Fig. 5, and plates having a thumb-screw shaped projection H, on the outside end are secured 30 by screws to the underside of the said braces I, I, and the table A (front end) is supported at any required angle by means of the table regulators, G, the plates, H, and the butt hinges, J, see Figs. 4 and 5.

35 The principle upon which my invention is successfully worked is as follows: The printed sheet is taken from the cylinder by the reel grippers, the same as heretofore, with the exception that the reel cam, shown in Fig. 3, causes the release of the sheet by 40 the reel grippers at a point eight or nine inches below the point of release needed by the fly system, but in my invention there are no fly sticks to rub against and mar the 45 printed sheet as so often happens in illustrated matter, instead, the stationary fingers, E, (four or more, according to size and width of printing press) are so arranged as to intercept the forward edge of 50 the printed sheet between the rim of the reel wheels and the reel gripper shaft and the sheet is then carried forward and under the fingers, E, about one and one-half inches before being released by the said grippers.

55 When released, the sheet is carried forward to the front face of the finger board, B, by its own momentum and the current of air which the rotation of the sheet itself upon

the reel wheels has caused to circulate, the sheet then falls from the reel wheels onto 60 the table A, and is stacked between the side sliding gages C, and the finger board B, with no other needed attention than the fixing of the sliding gages to meet the requirements of the width of sheet being printed. 65

Previous to my invention, if a correction was needed in the type when the form was in the press it was necessary to run the form to the front of the press, and in many instances, to remove the ink rollers. The 70 ease with which access to the form is given by my invention is well illustrated in Fig. 5, in which the table A, is shown raised in the table regulators G (the fly table, which formerly occupied several feet of floor space 75 at the back of the press being dispensed with and replaced in all its usefulness by the table A).

What I claim as my invention, and desire to secure by Letters Patent, is—

1. In a device of the class described the combination of a U-shaped table support detachably secured to the frame of a printing press; a section of a table superimposed on said support; another portion of said table hinged thereto; regulators to adjust one edge of the last mentioned section of said table; a finger board secured to and inclined over a portion of said first mentioned section of the table; finger members secured to said board adapted to engage the printed sheet on one of its edges before it is released and guide said sheet in its fall; and side guides adjustable on said table. 80

2. In a device of the class described the combination of a U-shaped table support secured to the frame of a printing press; a table section superimposed thereon; another portion of said table hinged thereto; regulators engaging therewith to adjust the 100 height of one edge of said table; a finger board secured to and inclined toward said table; fingers secured to said board; side and front guides on said table adapted to direct a sheet of printed matter on to said 105 table; and a cam to release said sheet from the reel of the printing press when it is engaged by said fingers.

In testimony whereof I have signed my name to this specification in the presence of 110 two subscribing witnesses.

GEORGE ACKERMAN.
